(57) **CLAIM**

The ornamental design for a pair of temple arms for an eyeglass frame with mount, as shown and described.

DESCRIPTION

FIG. 1 is a perspective view of a pair of temple arms with mount for the new design shown in the environment of an eyeglass frame;

FIG. 2 is a perspective view thereof;

FIG. 3 is a front elevational view thereof;

FIG. 4 is a rear elevational view thereof;

FIG. 5 is a side elevational view thereof;

FIG. 6 is a side elevational view thereof;

FIG. 7 is a side elevational view of the single temple arm with mount;

FIG. 8 is a side elevational view of the single temple arm without mount, wherein the other side is a mirror image thereof;

FIG. 9 is a top plan view thereof; and,

FIG. 10 is a bottom plan view thereof.

The broken lines showing the front of the eyeglass frame, mounted computer and other portions are for the purpose of illustrating environment structure and form no part of the claimed design.
